UNITED STATES PATENT OFFICE.

EDWIN W. WEBB, OF OAK PARK, ILLINOIS, ASSIGNOR, BY MESNE ASSIGNMENTS, TO THE FARLOW DRAFT GEAR COMPANY, OF BALTIMORE, MARYLAND, A CORPORATION OF DELAWARE.

DRAFT-GEAR.

1,004,511.

Specification of Letters Patent. Patented Sept. 26, 1911.

Application filed January 26, 1909, Serial No. 474,254. Renewed March 29, 1910. Serial No. 552,237.

To all whom it may concern:

Be it known that I, EDWIN W. WEBB, a citizen of the United States, residing at Oak Park, in the county of Cook and State 5 of Illinois, have invented certain new and useful Improvements in Draft-Gear, of which the following is a specification.

My invention relates in general to draft gear for railroad cars, and more particularly to the spring type of draft gear.

At the present time, the usual means employed for operatively connecting the draw-bar with the draft gear comprises a yoke extending around the draft gear and riveted 15 at its end to the top and bottom of the inner end of the draw-bar. This connecting means is open to the objection that the rivets often shear off, and to the further objection that in order to remove the draft gear from a 20 car the draw-bar must also be removed. In order to avoid these objections to the use of a connecting yoke, side links have been connected to the draw-bar by a key which may be withdrawn so as to permit the removal of the draft gear without detaching the draw-bar from the car. In this side link type of draft gear, when two sets of 25 springs are employed, it has been necessary to arrange them in vertical alinement, owing to the lack of practical means for simultaneously operating the springs when arranged in tandem. In many constructions of cars, it has heretofore been impossible to use the side link type of draw gear as 30 there is insufficient space to permit the two springs to be arranged in vertical alinement.

The primary object of my invention is to provide a side link draft gear in which the springs may be located in tandem and simultaneously compressed under both pulling 35 and buffing strains.

A further object of my invention is to provide an improved draft gear which will be simple in construction, inexpensive to 40 manufacture, and efficient in use.

My invention will be more fully described hereinafter with reference to the accompanying drawings, in which the same is illustrated as embodied in a convenient and practical form, and in which—

Figure 1 is a vertical sectional view through a draft gear, the adjacent portions of a car being shown in connection therewith. Fig. 2, an under plan view, looking 55 upwardly with respect to Fig. 1. Fig. 3, a transverse sectional view. Fig. 4, a per-

spective view of one of the followers. Fig. 5, a perspective view showing the other side of the follower. Fig. 6, a perspective view of one of the side links, and Fig. 7, a perspective view of one of the keys.

The same reference characters are used to designate the same parts in the several figures of the drawings.

Reference characters A', A² indicate portions of the center sills of a car.

Reference letter A indicates the car end sill.

Reference characters B' and B² indicate the draft timbers which are shown as consisting of channel beams. C' and C² indicate cheek plates secured to the inner surfaces of the draft beams and between which the draft gear is interposed.

D' indicates a draw-bar.

The above described parts do not in themselves constitute the novelty of my invention, as they are usually employed in connection with draft gear for operatively connecting the car coupler to the car frame. 75 The above parts are, however, illustrated and described, in order that the construction and operation of my invention will be fully understood. It will be obvious that my improved draft gear is not limited in its application to railroad cars comprising the specific parts above described, but may be used in connection with other specific forms of cooperating parts for operatively applying the same to a railroad car.

Reference characters E' and E² indicate side links each of which is provided with three elongated slots to be engaged by transverse keys. A key F' passes through the alined slots in the corresponding ends of the links E' and E² and through the slot in the rear end of the draw-bar which is interposed between the ends of the links. The lengths of the slots in the links and draw-bar which the key F' engages are such as to permit no 85 relative play between the draw-bar and the links. F² indicates a second key which passes through the alined intermediate slots in the two links, the slots being of such length as to permit no play between the key 95 and the links. F³ designates a third key which engages the alined slots in the inner ends of the links, the slots being longer than the width of the key so as to permit a relative longitudinal movement of the key and 105 links.

G' and G² indicate a pair of followers be-

tween which is interposed a coiled spring H'. The surface of each of the followers which is engaged by the corresponding end of the spring is provided with a stud g which extends within the spring, and is also provided with curved ribs g' which partially surround the end of the spring, the stud and ribs serving to securely seat the end of the spring against the follower. 5 Projecting laterally from the opposite side edges of each of the followers is a pair of spaced lugs g² which engage against stops on the cheek plates. The follower G' opposes against the inner end of the draw-bar 10 D when the parts are in their normal position, as shown in Fig. 2. The pairs of lugs g² on the follower G' permit the free movement between them of the links E' and E², and rest against the stops c', c' on the cheek 15 plates C' and C². The spaced lugs g², g² on the follower G² in a similar manner freely straddle the side links and rest upon the shoulders c², c² on the cheek plate. G³ and G⁴ indicate a similar pair of followers 20 between which is interposed a coiled spring H². The spaced side lugs of the followers G³ and G⁴ also freely straddle the side links and rest upon the shoulders c³, c³ and c⁴, c⁴, respectively, on the cheek plates. Each of 25 the followers on its surface opposite to that with which the adjacent spring engages is provided with two lugs g³ spaced apart a distance to permit one of the transverse keys to freely be received between them. It will 30 be seen by reference to Fig. 2 that the key F² is received between the pairs of lugs g³ on the followers G² and G³, while the corresponding lugs on the follower G⁴ receive 35 between them the key F³. Each of the keys F', F² and F³ extend through elongated 40 slots in the cheek plates and draft beams, cotter pins f, or other similar fastening devices, being provided in the ends of the keys to prevent their accidental lateral disengagement 45 from the draft sills.

The operation of my improved draft gear is as follows: When the parts are in the position shown in Fig. 2, a pulling strain exerted upon the draw-bar D effects a direct 50 pull upon the side links E' and E², which in turn exerts a direct pull upon the transverse keys F² and F³. The pull upon the key F² moves the follower G² toward the follower G', thereby compressing the spring H', owing to the stops c', c' preventing a forward 55 movement of the follower G'. A simultaneous forward movement is imparted to the follower G⁴ by the key F³, thereby compressing the spring H², owing to the follower G³ being prevented from forward 60 movement through engagement with the stops c³, c³ on the cheek plates.

When the draw-bar is subjected to a buffering strain, any inward movement of the 65 draw-bar effects a similar inward movement

of the follower G', owing to the direct contact of the inner end of the draw-bar with such follower. Such movement of the follower G' compresses the spring H', owing to the follower G² being retained against 70 inward movement through engagement with the stops c², c² on the cheek plates. Simultaneously with the inward movement of the follower G', a similar inward movement is imparted to the follower G³, through the 75 medium of the side links E' and E² and the transverse key F². Such movement of the follower G³ compresses the spring H², owing to the follower G⁴ being retained against inward movement through engagement with the stop c⁴, c⁴ on the cheek plates. It will be observed that the elongated slots 80 in the inner ends of the side links, through which the key F³ passes, permit the inward movement of the links. 85

When it is desired to detach the draft gear from the car for any purpose, such, for instance, as to make repairs, it is merely necessary to remove the cotter pins f from the corresponding ends of the transverse keys 90 and to then remove the keys, whereupon the side links, followers and interposed springs may be withdrawn downwardly from engagement with the draw-bar and cheek plates. The draft gear may be readily replaced into operative position by an upward movement and a re-insertion of the transverse keys through the alined slots the draft sills, cheek plates and links, the forward key also being passed through the slot 100 in the draw-bar.

By my improvement, the advantages of a side link draft gear are rendered available in connection with tandem springs, thereby also attaining the advantages of tandem springs 105 over springs arranged in vertical alinement.

While I have described more or less in detail the specific structure in which I have illustrated and described my invention as embodied, yet it is to be understood that my 110 invention is not to be limited thereto, but as covering other specific structures and arrangement of parts which may come within the scope of my improvement as defined by the following claims. 115

I claim:

1. The combination with the draft members, of cheek plates on the inner surfaces of the draft members, said plates having inwardly projecting transversely alined pairs 120 of stops thereon; a draw bar; two pairs of followers interposed between the cheek plates; two springs, one being interposed between the followers of each pair and movably retaining the followers against the adjacent pairs of stops; side links secured to the draw bar; and transverse keys connecting the links for transmitting to the followers movements of the draw bar relatively to the draft sills. 125

2. The combination with the draft members, of cheek plates secured to the inner surfaces of the draft members, said plates having inwardly projecting transversely alined pairs of stops thereon; a draw bar; parallel links secured at their front ends to the draw bar; two pairs of followers at the sides of which said links are freely movable, said followers having spaced side lugs above and below the links which engage the stops on the cheek plates; two springs, one interposed between the followers of each pair and movably retaining the followers against the adjacent pairs of stops; and transverse keys connecting the links for transmitting to the followers movements of the draw bar relatively to the draft sills.

3. The combination with the draft members, of cheek plates on the inner surfaces of the draft members, said plates having inwardly projecting transversely alined pairs of stops thereon; a draw bar; two pairs of followers interposed between the cheek plates; two springs, one interposed between the followers of each pair and movably retaining the followers against the adjacent pair of stops; side links secured to the draw bar; removable transverse keys connecting the links for transmitting to the followers movements of the draw bar relatively to the draft sills, said keys projecting at their ends through elongated slots in the cheek plates and draft members and constituting the sole support for the draft gear; and retaining devices for preventing accidental transverse motions of the keys out of engagement with the slots in the cheek plates and draft members.

4. The combination with the draft members, of cheek plates secured to the inner surfaces of the draft members and having inwardly projecting transversely alined pairs of stops thereon; a draw bar; parallel links having elongated slots at their ends and secured at their front ends to the draw bar; two pairs of followers at the sides of which said links are freely movable, said followers having spaced side lugs above and below the links which engage the stops on the cheek plates; two springs, one interposed between the followers of each pair and movably retaining the followers against the adjacent pair of stops; a transverse key uniting the front ends of said links to the draw bar; a second transverse key connecting and movable with the links and extending between the adjacent intermediate followers; and a third transverse key movably engaging the ends of the elongated slots in the inner end of the links and also engaging the adjacent surface of the inner follower.

5. In a side link tandem spring gear,

follower having spaced lugs at each side thereof adapted to engage stops on cheek plates and between which the links are 65 adapted to freely pass.

6. The combination in a draft gear, of slotted links, a transverse key, cushioning means, cheek plates with stops, and a follower having at one surface means adapted 70 to engage the transverse key located adjacent thereto and within the slots of the links and the other surface adapted to engage the cushioning means and also having spaced lugs at each side thereof adapted to 75 engage the stops on cheek plates and between which lugs the links freely pass.

7. The combination with the draw bar and draft members, of a tandem spring draft gear embracing links each link having 80 three slots with a key within the middle slots of each link and movable with the links in both directions, and means for detachably connecting the draft gear with both the draw bar and draft members consisting 85 of transverse movable keys, whereby by the removal of said keys the draft gear may be removed from the draft members without detaching the draw bar therefrom.

8. The combination in a draft gear, of 90 two draft members each having slots; slotted cheek plates having slots and stops; cushioning means; links with slots; followers having spaced lugs at each side thereof for the passage of links between the said 95 lugs; a slotted draw bar; and keys located within the slots of the draft members, links and draw bar; the key within the slots at the central portions of the links being of the same width as the length of the slots and 100 closely fitting the slots so as to move rearwardly therewith in buffering and forwardly therewith in drawing.

9. In a tandem spring draft gear, the combination with the draft members each 105 having a slot, of a key movable both forwardly and rearwardly within the slots; stops on the draft members adjacent to the key; two followers having spaced lugs and engaging the stops and adapted to be moved by the key alternately one forwardly and the other rearwardly; a front follower; a rear follower; cushioning means between the followers; a draw bar; and means located 110 between the spaced lugs of the followers for transmitting motion from the draw bar to the followers.

In testimony whereof, I have subscribed my name.

EDWIN W. WEBB.
